F. HAGGERTY.

FOOT BALL SIGNAL.

APPLICATION FILED SEPT. 26, 1916.

1,279,539.

Patented Sept. 24, 1918.

UNITED STATES PATENT OFFICE.

FRANK HAGGERTY, OF CHICAGO, ILLINOIS, ASSIGNOR OF ONE-FOURTH TO CHARLES IZENSTARK, OF CHICAGO, ILLINOIS.

FOOT-BALL SIGNAL.

1,279,539.

Specification of Letters Patent. Patented Sept. 24, 1918.

Application filed September 26, 1916. Serial No. 122,209.

To all whom it may concern:

Be it known that I, FRANK HAGGERTY, a citizen of the United States, and a resident of the city of Chicago, county of Cook, and 5 State of Illinois, have invented certain new and useful Foot-Ball Signals, of which the following is a specification.

My invention relates to a certain new and useful football signal, and has for its object 10 the provision of such a signal whereby the immediate situation of the game after each play or "down" may be readily indicated to the players and to the spectators.

A further object of the invention is to 15 provide a construction of this character which is simple, capable of economical manufacture, and is highly efficient in use.

Other objects will appear hereinafter.

With these objects in view, the invention 20 consists in the combinations and arrangements of parts hereinafter described and claimed.

The invention will be best understood by 25 reference to the accompanying drawings forming a part of this specification, and in which,

Figure 1 is a face view of a signal embodying my invention,

Fig. 2, a side view of the same,

Fig. 3, a top plan view of the same in a slightly different position,

Fig. 4, a side view of the upper portion of the signal, shown in the same position as that indicated in Fig. 3,

Fig. 5, a detail section taken through one end of the signal, and

Fig. 6, a view illustrating one of the signal bodies folded for transportation.

The preferred form of construction, as 40 illustrated in the drawings, comprises a suitable supporting pole 7 which is shown in the form of a simple iron pipe which, of course, may be made in two or more sections if desired. Arranged at the end of the pole

45 7 are signal bodies 8 and 9 which are similarly constructed and mounted and are in all essential respects identical in construction, the only difference being that they are oppositely positioned on the pole, and the 50 sides of which are differently numbered.

Each of these signal bodies is substantially cubical in form and comprise the opposite sides 10 and 11 and opposite sides 12 and 13 hinged together at the corners for folding, 55 as indicated in Figs. 3 and 6. The opposite

sides 10 and 11 of the body 8 are prominently marked with the numeral 1 while the opposite sides 12 and 13 of the body 8 are prominently marked with the numeral 2. Likewise the opposite sides 10 and 11 of the signal body 9 are prominently marked with the numeral 3, and sides 12 and 13 with the numeral 4, as indicated. A top member 14 is provided for each of the signal bodies, said member 14 being hinged at 15 to the upper edge of the corresponding side 10 and being provided with a snap fastening 16 on the opposite side 11 arranged to engage the opposite edge of said top.

By this arrangement the signal bodies 70 may be readily collapsed and folded, as indicated in Fig. 6, or distended into tubular form and held in such tubular form by forcing the top member into position between the side members, as indicated. Each of the 75 top members 14 is centrally perforated and provided with a nut 17 threaded to screw onto the ends of the pole 7 which are correspondingly threaded, as indicated. Likewise a spike member 18 is threaded into each 80 end of the pole 7 to constitute a convenient means for positioning the pole on the ground in an upright position. By this arrangement, it will be observed that the pole 7 may be readily positioned on the ground 85 with either end uppermost and may be turned to present the sides of the upper signal body in any desired direction.

The pole 7 is provided with perforations 19 adjacent the signal bodies 8 or 9, and a 90 substantially rectangular signal frame 20 is provided with an angularly positioned stem 21 adapted to be inserted through said perforations to serve as a support for said signal frame and to permit of ready re-adjustments thereof. The signal frame 20 is provided with two guide loops 22 upon which a plurality of signal plates 23 are arranged to slide, each being provided with perforations 24 sliding on said loops. The plates 23 are 100 used for indicating necessary yards to gain, and for convenience the plates 23 are numbered consecutively from 1 to 10 inclusive and 15, 20, 25 and 30.

In use, the signal is preferably carried by 105 the head-linesman who positions the same on the side line of the football field registering with the longitudinal position of the ball thereon. At the same time the head-linesman turns the signal to indicate upon one of 110

the bodies 8 or 9 the number of the impending down, and also adjusts the signal plates 23 to indicate the yards necessary to be gained in the allotted number of downs. 5 The signal body 8 is used by the head-linesman to indicate downs 1 and 2, he preferably positioning the signal, at the top of the pole, with the faces thereof indicating the number of the impending down facing up and 10 down the field, and also preferably positioning the signal frame 20 on the side facing the team having the ball. For downs 3 and 4, the position of the pole is reversed to bring the signal body 9 at the top thereof 15 and the frame is shifted into the perforation 19 just under the signal body 9, the downs and the yards to gain being indicated as before.

When not in use, the parts may be readily 20 taken apart and the signal bodies folded, as indicated in Fig. 6, for convenience in transportation.

While I have illustrated and described the preferred form of construction for carrying 25 my invention into effect, this is capable of variation and modification without departing from the spirit of the invention. I, therefore, do not wish to be limited to the precise details of construction set forth, but 30 desire to avail myself of such variations and modifications as come within the scope of the appended claims.

Having described my invention what I 35 claim as new and desire to secure by Letters Patent is:

1. A football signal comprising a pole; and a signal body at each end thereof, said bodies being oppositely arranged with re-

spect to each other, substantially as described.

40

2. A football signal comprising a pole; and a signal body at each end thereof, said bodies being oppositely arranged with respect to each other and having their opposite sides similarly marked, substantially as de- 45 scribed.

3. A foot ball signal comprising a pole; and a signal body on each end thereof arranged to indicate downs and to become operative or inoperative upon reversals of said 50 pole, substantially as described.

4. A football signal comprising a pole; and a collapsible signal body removably mounted on each end thereof arranged to indicate downs and to become operative or 55 inoperative upon reversals of said pole, substantially as described.

5. A football signal comprising a pole; and a collapsible signal body removably mounted at each end thereof, said bodies being oppositely arranged with respect to each 60 other, substantially as described.

6. A football signal comprising a pole; and a collapsible signal body removably mounted at each end thereof, said bodies being oppositely arranged with respect to each other and having their opposite sides similarly marked, substantially as described. 65

In testimony whereof I have signed my name to this specification in the presence of 70 two subscribing witnesses.

FRANK HAGGERTY.
